UNITED STATES PATENT OFFICE.

ROBERT FRANKLIN RINGLE, OF ZELIENOPLE, PENNSYLVANIA, ASSIGNOR TO HERMAN PNEUMATIC MACHINE COMPANY, OF ZELIENOPLE, PENNSYLVANIA, A CORPORATION OF PENNSYLVANIA.

VALVE FOR JARRING-MACHINES.

1,083,761.

Specification of Letters Patent.

Patented Jan. 6, 1914.

Application filed June 27, 1911. Serial No. 635,673.

To all whom it may concern:

Be it known that I, ROBERT FRANKLIN RINGLE, a resident of Zelienople in the county of Butler and State of Pennsylvania, have invented a new and useful Improvement in Valves for Jarring-Machines; and I do hereby declare the following to be a full, clear, and exact description thereof.

My invention relates to molding machines, and has special reference to what are known as jarring machines for forming sand molds.

The object of my invention is to provide a cheap, simple and efficient form of controlling device to govern the movements of such machines in their jarring operation, and one which will be automatic in operation and constructed of few and durable parts so that there will be practically no danger of said device getting out of order.

My invention consists, generally stated, in the novel arrangement, construction and combination of parts, as hereinafter more specifically set forth and described and particularly pointed out in the claims.

To enable others skilled in the art to which my invention appertains to construct and use my improved molding machine, I will describe the same more fully, referring to the accompanying drawing, in which—

Figure 1 is a central section of my improved molding machine showing the valve and plunger in one position. Fig. 2 is a central section of the valve and part of the plunger in its other position.

Like symbols of reference herein indicate like parts in each of the figures of the drawing.

As illustrated in the drawing, 1 represents the base of the machine, which has the casing 2 of rectangular shape extending up from the same, and within said casing and formed as part of the same is the cylinder 3. This cylinder 3 is positioned vertically within the casing 2 and has a series of vertical wings 4 connecting the outer sides of the same with the inner sides of said casing, while a cross wall 5 is formed in the lower end of said cylinder, and above the same is an opening 6 through which an operating fluid, such as air, is admitted from the differential control valve A for operating the same, while an operating port 6' is located in said cylinder directly above the opening

6, and safety ports 6" are located above said operating port and at intervals around the same. Within the cylinder 3 and above the cross wall 5 therein is the plunger 7, which is provided with an exhaust opening 7' near the lower end of the same for communicating at intervals with the opening 6' in cylinder 3, while said plunger is also provided with an opening 7" above said cylinder and diametrically opposite to said exhaust opening, and said plunger is connected at its upper end to a table or pattern plate 9, and such plate extends over the top of the casing 2 and is of rectangular shape in an inverted cup-shaped form, so that its outer annular flange 10 extending down from the outer edge of the same will fit around the upper edge of such casing when the plate is in its lowered position. Extending down from the under face 11, which is connected to the plunger 7 by a series of wings or ribs 12 at each corner of the same and intermediate of said corners is a post or enlargement 13 extending around said flange from the bottom of the plate 9, to a point below said flange. Below each of the enlargements 13 is a jarring post or bracket 14 which is formed as part of and extends inward from the inner face of the casing 2, and each of said posts is provided with an angular rib 15 connecting the bottom of the same with the inner side of the casing. Within the upper face of the posts 14 is a seat 16 for the reception of a resilient jarring block 17, preferably formed of rubber, or other suitable flexible material, and fitting within said seat and against each of the upper faces of said block is a wearing block plate 18, which extends above its seat and is adapted to engage with the post 13 in line with the same in the jarring operation.

Situated at a point substantially near the bottom of plunger 7 and connected to the outer face of the cylinder 3 within the casing 2 is the differential control valve A which has its body 19 secured to said cylinder by bolts 20 passing through flanges 21 to support the same. The valve body 19 is provided at its upper end with a top cover 22 which fits over the same and is secured thereto by means of the bolts 23, while the lower end of said body is provided with a bottom cover 24, which is secured thereto by means of bolts 25 fitting into the same. Con-

necting to the lower end of the bottom cover 24 and fitting therein by means of the screw thread 26' is the supply pipe 26 which communicates with the inlet seat 27 in said bottom cover, and said inlet seat has the four passageways 28 therein which communicate with the passageway 29 in the valve body 19, which passageway in turn communicates with the opening 6 in the cylinder 3.

Immediately above the passageway 29 in the valve casing or body 19 and communicating therewith is an exhaust opening 30 which leads into the exhaust chamber 31 immediately above the same, which is provided with an exhaust pipe 31' leading therefrom, while a piston cylinder 32 is located at the upper end of said valve body and is inclosed at its upper end with the top cover 22 which has a recessed center 33 therein, while said cover is also provided with a small recess 34 for communicating with a passageway 35 in said valve body, which communicates with the opening 6' in the cylinder 3. In the upper end of the valve body 19 and opposite the piston cylinder 32 is an auxiliary check valve 36 which is mounted on a spring 37, and the tension of such spring is regulated by the valve cap 38, which bears against said spring, while a passageway 39 leads in a horizontal direction from said valve to the passageway 35 in said body, and another passageway 40 leads in a vertical direction from said valve to the passageway 35. Within the passageway 35 and between the points where the passageways 39 and 40 communicate with the same is a stroke regulating valve 41 which is adapted to be adjusted by the operator to regulate the length of the stroke of the plunger 7 in the cylinder 3.

Within the piston cylinder 32 is a valve device having a piston 42 which operates within the same and has a stem 42' extending downward from the same through the exhaust chamber 31 and opening 30. This stem 42' is provided at its lower end with a head or flanged portion 43, and terminates in a shank 44, which engages by the valve face 44' at its lower end with the inlet seat 27 in the bottom cover 24. The head 43 has a valve face 43' at the upper end of the same for engaging with a valve seat 30' above the passageway 29, and the piston 42 in the piston cylinder 32 is provided with the ordinary rings 45 around the same to prevent leakage of the operating fluid by reason of the wear occasioned by the movement of said piston in said cylinder.

The use and operation of my improved apparatus is as follows:—Considering the piston in its lowered position such as is shown in Fig. 2, the operating fluid enters through the supply pipe 26 and raises the piston to a position such as shown in Fig.

1, whereupon said fluid passes through the inlet seat 27 and through the passageways 28 and 29 and enters the cylinder 3 through the opening 6 beneath the plunger 7, thereby raising said piston until the bottom of the same opens the valve operating port 6', whereupon the operating fluid enters the passageway 35 and through the recess 34 and bears against the upper face of the piston forcing the same downward and shutting off the operating fluid supply, whereupon the plunger 7 in the cylinder 3 will drop down in said cylinder and the posts 13 on the table 9 will strike upon the jarring post 14, while the fluid in said cylinder and below said plunger will be expelled therefrom through the opening 6 in the cylinder 3, the passageway 29, the exhaust opening 30, the exhaust chamber 31, and into the exhaust pipe 31'. When the plunger 7 has reached its lowered position in the cylinder 3 the exhaust opening 7' in said plunger will communicate with the valve operating port 6' in the cylinder 3, thus allowing the fluid in the cylinder 32 to exhaust through the recess 34 and passageway 35 and said valve operating port and opening into the interior of said plunger, whence it is exhausted from the opening 7" into the casting 2. The machine is now ready for another operation and is accomplished in the manner described, so that the jarring is repeated until the sand in the mold is packed to the required degree of solidity.

The length of the stroke of the plunger 7 in the cylinder 3 is regulated by means of the stroke regulating valve 41, which is adapted to diminish and increase the amount of operating fluid which passes through the passageway 35, so that when said valve has been regulated so as to allow only a small amount of the fluid to pass through the same and into the piston cylinder 32 for lowering the piston 42 therein and thus cutting off the supply of fluid from the inlet seat 25, the plunger 7 in the cylinder 3 will continue to travel upward until sufficient fluid has entered the first named cylinder to lower said piston. When the above operation has been accomplished and the plunger 7 in the cylinder 3 has been dropped to jar the same, the fluid in the cylinder 32 will be expelled by the raising of the piston 42 and to prevent the necessity of such fluid passing through the diminished regulating valve 41, for exhausting the same through the operating port 6' in the cylinder 3 and exhaust opening 7' in the plunger, said fluid will enter the passageway 39 and will open the auxiliary check valve 36 and pass downward through the passageway 40 into the passageway 35 and exhaust in the manner described. This auxiliary check valve 36 will thus prevent the necessity of the plunger 7 remaining in its lowered position until all the fluid

in the cylinder 32 has been exhausted through the regulating valve 41 when such valve has been regulated to reduce the amount of fluid flowing through the same.

- 5 In the use of my improved valve there is a great advantage over the ordinary form of control of jarring machines, in that, when a superfluous amount of the operating fluid is admitted to the cylinder and under the 10 plunger therein, there is no way of detecting this waste of energy, as the fluid is all discharged almost instantaneously from said cylinder to allow the plunger to drop, while with the use of my improved valve the exhaust passageway is so regulated that the 15 fluid in discharging must all pass therethrough, so that if too much pressure was being applied to lifting the plunger in said cylinder the fluid would not have time to 20 escape through the valve before the plunger had dropped the distance required to allow the jarring of the mold, but the fluid in the cylinder which had not had time to escape would form a cushion in said cylinder 25 against which said plunger would drop so that there would be no jarring by the plate striking the jarring blocks, and the operator will thus be warned to diminish the supply of fluid to the cylinder. It will also be 30 readily seen that my improved valve is automatic and self contained and does not depend for its operation upon any hooks, levers, tripping devices, springs or any external mechanism, and that since said valve 35 is entirely inclosed no dirt or sand can come in contact with any of the working parts of the same and thus cause injury. The travel of the valve stem and piston is so small that there will be very little jarring 40 of the same, so that the wear thus occasioned will be reduced to a minimum, and by the arrangement of the parts in my improved valve, the plunger will be given a perfect upward and downward stroke and will start 45 upward immediately after the table has struck upon the jarring blocks, thus insuring an even and regular movement.

What I claim as my invention and desire to secure by Letters Patent is—

- 50 1. In combination with a jarring machine having a cylinder provided with a port therein and a plunger within said cylinder, a valve casing connecting with said port having opposed faces above and below said port, and a double-faced valve in said casing between said faces for allowing the admission of operating fluid to said cylinder through said port for raising said plunger and adapted to be reversed by means of a 55 piston above and connected to said valve when said plunger has reached its raised position, thereby cutting off the admission of fluid to said cylinder to allow the fluid therein to exhaust through said port and permit said 60 plunger to drop in said cylinder.

2. In combination with a jarring machine having a cylinder provided with a port therein with an opening above the same and a plunger within said cylinder, a valve casing connecting with said port and opening having opposed faces above and below said port, and a double-faced valve within said casing between said faces for allowing the admission of operating fluid to said cylinder through said port for raising said plunger 70 and adapted to be reversed by means of a piston above and connected to said valve when said plunger has reached its raised position, by the fluid passing through said opening, thereby cutting off the admission of fluid to said cylinder to allow the fluid therein to exhaust through said port and permit said plunger to drop in said cylinder. 75

3. In combination with a jarring machine having a cylinder provided with a port therein with an opening above said port and a plunger within said cylinder, a valve casing connecting with said port and opening having opposed faces above and below said port, and a double-faced valve within said casing between said faces having a piston connected to the upper end thereof, said valve allowing the admission of operating fluid to said cylinder through said port for 80 raising said plunger and adapted to be reversed when said plunger has reached its raised position by the fluid passing through said opening and to one end of said piston, thereby cutting off the admission of fluid to 85 said cylinder to allow the fluid therein to exhaust through said port and permit said plunger to drop in said cylinder. 90

4. In combination with a jarring machine having a cylinder provided with a port therein with an opening above said port and a plunger within said cylinder, a valve casing connecting with said port and opening having opposed faces above and below said port, a double-faced valve within said casing 100 between said faces having a piston connected to the upper end thereof, and a passageway in said casing communicating with one end of said piston and opening, said valve allowing the admission of operating fluid to said cylinder through said port for raising said plunger and adapted to be reversed when said plunger has reached its raised position by the fluid passing through said opening and passageway and above said piston, thereby cutting off the admission of fluid to 105 said cylinder to allow the fluid therein to exhaust through said port and permit said plunger to drop in said cylinder. 110

5. In combination with a jarring machine 115 having a cylinder provided with a port therein with an opening above said port and a plunger within said cylinder, a valve casing connecting with said port and opening having opposed faces above and below 120

130

said port, a double faced valve within said casing between said faces having a piston connected to the upper end thereof, and a passageway in said casing communicating 5 with one end of said piston and opening, another passageway in said casing communicating with said port, said valve being adapted to engage with the upper face to allow the admission of operating fluid to 10 10 said cylinder through said last named passageway and said port for raising said plunger and adapted to engage with the lower face when said plunger has reached its raised position by said fluid passing through 15 15 said opening and first named passageway and above said piston, thereby cutting off the admission of fluid to said cylinder to allow the fluid therein to exhaust through said port and permit said plunger to drop 20 in said cylinder.

6. In combination with a jarring machine having a cylinder provided with a port therein with an opening above said port and a plunger within said cylinder, a valve 25 casing connecting with said port and opening having opposed faces above and below said port, a valve within said casing between said faces having a piston connected to the upper end thereof, said valve allowing the 30 admission of operating fluid to said cylinder through said port for raising said plunger and adapted to be reversed when said plunger has reached its raised position by the fluid passing through said opening and 35 through a passageway leading to one end of said piston, thereby cutting off the admission of fluid to said cylinder to allow the fluid therein to exhaust through said port and permit said plunger to drop in said cylinder, and means in said passageway to control the rate of flow of fluid passing through the same to lower said piston.

7. In combination with a jarring machine having a cylinder provided with a port 45 therein with an opening above said port and a plunger within said cylinder, a valve casing connecting with said port and opening, a valve within said casing having a piston at the upper end thereof, said valve allowing the admission of operating fluid to said cylinder through said port for raising said plunger and adapted to be reversed when 50 said plunger has reached its raised position by the fluid passing through said opening and through a passageway leading to one end of said piston, thereby cutting off the admission of fluid to said cylinder to allow the fluid therein to exhaust through said port and permit said plunger to drop in 55 said cylinder, and through a passageway leading to one end of said piston, thereby cutting off the admission of fluid to said cylinder to allow the fluid therein to exhaust through said port and permit said plunger to drop in said cylinder, and a stroke regulating valve in said last named passageway to control the rate of 60

flow of fluid passing through the same to lower said piston.

8. In combination with a jarring machine having a cylinder provided with a port 65 therein with an opening above said port and a plunger within said cylinder, a valve casing connecting with said port and opening, a valve within said casing having a piston at the upper end thereof, said valve 70 allowing the admission of operating fluid to said cylinder through said port for raising said plunger and adapted to be reversed when said plunger has reached its raised position by the fluid passing through 75 said opening and through a passageway leading to one end of said piston, thereby cutting off the admission of fluid to said cylinder to allow the fluid therein to exhaust through said port and permit said plunger 80 to drop in said cylinder, means in said passageway to control the rate of flow of fluid passing through the same to lower said piston, and a passageway communicating with said first named passageway and on each 85 side of said means and adapted to exhaust the fluid from the end of said piston on its upward stroke.

9. In combination with a jarring machine having a cylinder provided with a port 90 therein with an opening above said port and a plunger within said cylinder, a valve casing connecting with said port and opening, a valve within said casing having a piston at the upper end thereof, said valve allowing the admission of operating fluid to said cylinder through said port for raising said plunger and adapted to be reversed when 95 said plunger has reached its raised position by the fluid passing through said opening and through a passageway leading to one end of said piston, thereby cutting off the admission of fluid to said cylinder to allow the fluid therein to exhaust through said port and permit said plunger to drop in 100 said cylinder, means in said passageway to control the rate of flow of fluid passing through the same to lower said piston, a passageway communicating with said first 105 named passageway and on each side of said means, and a spring operated check valve in said last named passageway to permit the exhausting of the fluid through said passageway from the end of said piston on its upward stroke.

In testimony whereof, I, the said ROBERT FRANKLIN RINGLE, have hereunto set my hand.

ROBERT FRANKLIN RINGLE.
